(57) **CLAIM**

The ornamental design for a document imaging instrument, as shown and described.

DESCRIPTION

FIG. 1 is a perspective view of a document imaging instrument, shown in a closed position;

FIG. 2 is a left side view of the document imaging instrument shown in FIG. 1;

FIG. 3 is a right side view of the document imaging instrument shown in FIG. 1;

FIG. 4 is a rear view of the document imaging instrument shown in FIG. 1;

FIG. 5 is a front view of the document imaging instrument shown in FIG. 1;

FIG. 6 is a top view of a document imaging instrument shown in FIG. 1;

FIG. 7 is a bottom view of the document imaging instrument shown in FIG. 1;

FIG. 8 is a perspective view of the document imaging instrument, shown in an open position;

FIG. 9 is a top view of the document imaging instrument shown in FIG. 8;

FIG. 10 is a bottom view of the document imaging instrument shown in FIG. 8;

FIG. 11 is a rear view of the document imaging instrument shown in FIG. 8;

FIG. 12 is a front view of the document imaging instrument shown in FIG. 8;

FIG. 13 is a left side view of the document imaging instrument shown in FIG. 8; and,

FIG. 14 is a right side view of the document imaging instrument shown in FIG. 8.

Broken lines and portions contained within broken lines are not claimed.
